UNITED STATES PATENT OFFICE.

FRANK A. LUNDQUIST, OF NEW YORK, N. Y., ASSIGNOR TO WESTERN ELECTRIC COMPANY, INCORPORATED, OF NEW YORK, N. Y., A CORPORATION OF NEW YORK

TELEPHONE SWITCHING SYSTEM.

1,251,545.

Specification of Letters Patent.

Patented Jan. 1, 1918.

Application filed November 15, 1916. Serial No. 131,457.

To all whom it may concern:

Be it known that I, FRANK A. LUNDQUIST, a citizen of the United States, residing at New York, in the county of New York and 5 State of New York, have invented certain new and useful Improvements in Telephone Switching Systems, of which the following is a full, clear, concise, and exact description.

10 This invention relates to telephone switching systems of the class in which connection is made between a call initiating line and a connecting circuit by means of automatically operating mechanism, the operation of 15 which is controlled by the operation of closing the line circuit by removing the receiver from the switchhook in initiating a call. The object of this invention is to provide means whereby the operating mechanism will not 20 respond to the condition existing upon a called line at the termination of a conversation when the called party is the last to hang up his receiver, whereby connecting circuits will not be unnecessarily seized by 25 the operation of said mechanism.

In general this invention consists in the provision of means whereby the operation, responsive to energization of the cut-off relay of a called line before the operation of 30 the line relay of that line, will disable the operating circuit of the switching mechanism associated with that line and will maintain it disabled until both the line and cut-off relays have been deenergized by the dis- 35 connection of the two lines and the opening of the called subscriber's telephone line at the substation.

More specifically, this invention consists of the provision of a circuit breaker in the 40 operating circuit of the switching mechanism, which circuit breaker is operated in response to the operation of the cut-off relay to open the circuit through the switching mechanism and is moved again into circuit closing position by means of an electromagnet, the circuit for the winding of which is completed only upon the deenergization of both the line and cut-off relays.

In the drawings, Figure 1 is a diagram

of apparatus and circuits illustrating this 50 invention; Figs. 2 and 3 are diagrams illustrating the position assumed in the operation of the parts embodying the features of this invention.

In Fig. 1, in which a part of an automatic 55 telephone system is illustrated schematically, 2 and 3 represent subscribers' stations which are adapted to be connected for conversation through the agency of switch contacts 5, 5, 5, 6, 6, 6 and 7, 7, 7, which contacts 60 may be controlled by automatic switches, or in any suitable way. The apparatus at each of the subscribers' stations 2 and 3 is of a well-known and standard type, and need not 65 be described herein.

The invention may be best understood by a description of the operation of a system.

Assuming subscriber's station 2 to be that of the calling subscriber and station 3 that of the called subscriber, and that the connection has already been extended to the called line through the operation of the switches 5, 5, 5, 6, 6, 6 and 7, 7, 7 in a well-known manner, we will consider the condition now existing. In the first place, a cut-off relay 10, associated with the line of the called station 3, will be energized over a circuit including the lower ones of the contacts 5, 6 and 7. Upon energization of the winding of the cut-off relay 10 an armature 11 80 is attracted. At its lower end this armature is adapted to operate contact anvils 12 and 13, and is provided near its upper end with a finger 14 extending at right angles thereto, and on its upper end with an insulating but- 85 ton 15. Upon the movement of the armature 11, in response to the energization of the cut-off relay winding, its lower end causes the contact anvils 12 and 13 to be moved away from engagement with contacts 16 and 17 in the circuit of a line relay 18.

This movement of the armature 11 also disengages the upper or insulated end from a projection 20 on a circuit breaking arm 21, which drops and opens a contact 22 included 90 in a circuit of a switching mechanism 23 by means of which a calling line is automatically associated with an idle connecting cir- 95

cuit. The switch may be of the type which automatically hunts the calling line, or the type which automatically hunts an idle connecting circuit, both being well-known in the art.

Upon the movement of the armature 11, the finger 14 thereon engages a contact anvil 25 of the line relay 18, thereby causing said anvil to close a contact 27, which is also included in the circuit of the switching mechanism 23. The closing of contact 27 would ordinarily complete the circuit of the switching mechanism 23, but owing to the condition established by the operation of the cut-off relay 10, this circuit is open at the contact 22. The parts will remain in the position illustrated in Fig. 2 so long as the two lines are connected for conversation.

At the completion of the conversation both subscribers will hang up their receivers in the usual manner. The hanging up of the calling subscriber's receiver will cause the opening of contacts 5, 5, 5, 6, 6, 6 and 7, 7, 7, and thereby break the circuit through the winding of the cut-off relay 10 whereupon a spring 30 draws the armature 11 back to normal position against a stop 31 and with a metallic portion thereof in electrical contact with the projection 20 on the arm 21. If at this time the called subscriber's receiver has not been returned to the switchhook the line relay 18 will be energized due to the closure of contacts 16 and 17 of the cut-off relay, and the contact 27 of the line relay will remain closed and the various parts will remain in the position shown in Fig. 3 with the circuit through the switching mechanism 23 open at the contact 22. If, however, the called subscriber has opened his line circuit, then the line relay 18 will be deenergized, and the contact anvil 25 thereon will be in engagement with the projection 14 on the armature 11, and a circuit will be closed from battery 35 through contact anvil 25, armature 11, circuit breaking arm 21 and winding of an electromagnet 37 to ground. The energization of the winding of electromagnet 37 causes it to attract the arm 21, whereby it is swung into position with the projection 20 thereon resting upon the insulating button 15 on the armature 11, thereby closing contact 21, as shown in Fig. 1, thereby placing the circuit of the switch 23 in condition to receive current from battery 35 upon energization of the line relay 18.

What is claimed is:

1. In a telephone switching system, calling and called lines, switching mechanism associated with each of said lines and operating automatically upon the closure of a calling line to connect said calling line with an idle connecting circuit, line and cut-off relays associated with each of said lines, and means

controlled by said line and cut-off relays for preventing the operation of the switching mechanism of a called line when said called line is held closed after disconnection of the calling line.

2. In a telephone switching system, calling and called lines, switching mechanism associated with each of said lines adapted upon the initiation of a call to connect the calling line with an idle connecting circuit, a cut-off relay associated with the called line and adapted to be energized and deenergized upon the connection and disconnection of a calling line with the called line, a line relay associated with said called line and adapted to be operated through normally closed contacts of said cut-off relay when the line associated therewith is closed, an operating circuit for said switching mechanism controlled by said line relay, and means controlled by said cut-off relay over the calling line to disable said switching mechanism operating circuit until the called line is opened.

3. In a telephone switching system, subscribers' lines, a connecting circuit common to a plurality of subscribers' lines, switching mechanism associated with said subscriber's line for connecting it with an idle connecting circuit upon the initiation of a call thereover, an operating circuit for said switching mechanism, a line relay for controlling said operating circuit, a cut-off relay for normally controlling the operation of said line relay, and means controlled by the energization of said cut-off relay for disabling the operating circuit of said switching mechanism and by a subsequent deenergization thereof and of the line relay for rendering said operating circuit responsive to a subsequent energization of said line relay.

4. In a telephone switching system, a subscriber's line, a connecting circuit, switching mechanism associated with a subscriber's line and adapted upon the initiation of a call thereover to connect said subscriber's line with a connecting circuit, an operating circuit for said switching mechanism, a line relay adapted to close said circuit, a cut-off relay, circuit breaking means operated upon the energization of said cut-off relay for disabling said operating circuit, and means for restoring said circuit breaking means controlled by the deenergization of said line relay.

5. In a telephone switching system, a subscriber's line, a connecting circuit, switching mechanism associated with said subscriber's line and adapted upon the initiation of a call thereover to connect said subscriber's line with a connecting circuit, an operating circuit for said switching mechanism, a line relay adapted to close said circuit, a pivotal

lever contact controlled thereby for disabling said operating circuit, a cut-off relay, a second lever controlled by the energization of said cut-off relay for causing the operation of said first mentioned lever to open its contacts, an electromagnet for restoring said first mentioned lever to circuit closing position, and an energizing circuit for said

electromagnet closed through the armature of said line relay in its normal position and 10 including said levers.

In witness whereof, I hereunto subscribe my name this 14th day of November, A. D. 1916.

FRANK A. LUNDQUIST.
